UNITED STATES PATENT OFFICE.

JONATHAN PETERSON, OF BROOKLYN, NEW YORK, ASSIGNOR TO COMBINATION MANUFACTURING COMPANY, OF NEW YORK, N. Y., A CORPORATION OF DELAWARE.

PACKAGE OR CONTAINER FOR TOBACCO OR SIMILAR COMMODITIES.

Application filed July 17, 1923. Serial No. 652,065.

To all whom it may concern:

Be it known that I, JONATHAN PETERSON, a citizen of the United States, and resident of Brooklyn, in the county of Kings and State of New York, have invented certain new and useful Improvements in Packages or Containers for Tobacco or Similar Commodities, of which the following is a specification.

10 My invention relates to improvements in packages or containers for tobacco or similar commodities.

Smoking tobacco in small quantities suitable for individual consumers, is frequently packed in rectangular paper bags or containers, and in order to preserve the tobacco in fresh condition until the package is opened, and after opening, for a reasonable time until the contents can be consumed, it has been customary to provide a composite inner package or wrapping consisting of sheets of paper and foil, this inner wrapping being formed into a bag or pouch of substantially rectangular form to correspond with the desired rectangular formation of the complete package, consisting of the inner wrapping with its contents and the outer pouch or bag.

The inner composite wrapper is usually formed with a "solid" (or flat, one-piece, foldless) bottom and with longitudinal folds and overlaps along the narrow sides of the package, and with short inner flaps or tuck folds at the bottom of the narrow sides produced in the formation of the longitudinal folds and flaps. In filling the inner wrappers, these bottom flaps or tuck-folds are frequently displaced or crumpled downward, permitting tobacco to spill out, and otherwise interfering with the proper filling and formation of the package; it is also difficult to properly secure the longitudinal margins of the side fold formation because the inner wrapper, as above stated, is a composite structure consisting of foil and paper, and in forming the longitudinal overlaps foil must be brought in contact with paper surfaces and it is difficult to properly adhesively secure these materials together in the commercial production of these packages.

Difficulty is also experienced with the composite inner wrappers, comprising a sheet of foil, which is frequently quite thick, in folding and closing the upper (closure)

end of the inner wrapper, which when folded is apt to be very thick and bulky at the ends, to such an extent that it is difficult to properly fold the upper end of the outer wrapper and produce the desired smooth flat top formation of the completed package; also when the package has once been opened to discharge part of the contents, it is difficult to again neatly and compactly fold the top portions of the inner wrapper without time-consuming care on the part of the user.

To overcome the foregoing and other difficulties, and at the same time to produce an improved package, having greater strength, durability, security, and capable of being more easily and compactly folded and secured both in the original completion of the package and after the top closure has been opened for removal of part of the contents of the individual consumer, my invention briefly described, provides an inner reenforcing and securing strip of suitable sheet material, usually paper, inserted within the composite inner wrapper and adhesively secured to paper portions of the composite wrapper along the narrow longitudinal side fold formations, and also internally overlying and secured to the bottom tuck-folds previously referred to. Since this connecting or reenforcing strip is adhesively applied to paper portions of the composite inner wrapper, the adhesive connection may be made satisfactorily secure and permanent without any reasonable possibility of the parts becoming separated during the life of the package. The inner wrapping or package is therefore held securely in proper form and at the same time any displacement of the bottom tuck-folds or flaps is effectively prevented by the smoothly applied and continuous inner reenforcing strip.

The invention also comprises a new and improved formation of the upper or closure portion of the inner composite wrapper, permitting a new method of folding the neck of the inner wrapper, this is, the portions projecting above the contents of the package, whereby a compact and flat mouth-end formation of the complete package may be produced in the original manufacture of the article, and moreover the neck or mouth portions may be easily and quickly refolded by the individual user after the package has

once been opened, to insure the proper retention of the contents and to protect the same against drying during the life of the package and also to preserve the compact and convenient form of the package for pocket-carrying until the contents is exhausted.

The invention also includes other features of package structure sufficiently explained hereafter.

The accompanying drawings illustrate certain representative embodiments of the invention. After considering these, persons skilled in the art will understand that many variations may be made within the principles of the invention, and I contemplate the employment of any structures that are properly within the scope of the appended claims.

Figure 1 is a perspective view of one suitable form of inner composite wrapper blank.

Figure 2 is a similar view of another suitable form of inner wrapper.

Figure 3 shows a convenient way of associating a reenforcing or connecting strip with a plunger preliminary to the formation of the inner container.

Figure 4 shows the initial application of the reenforcing strip to the inner wrapper.

Figure 5 shows the inner wrapper partly folded upon the plunger.

Figure 6 shows another folding step.

Figure 7 shows the inner container completely folded or formed, and an outer wrapper about to be placed upon the inner container.

Figure 8 shows the outer wrapper completely formed about the inner container.

Figure 9 shows inner container closure flaps folded down in overlapped relation.

Figure 10 shows the closure or neck of the outer wrapper partly folded.

Figure 11 shows the package completely closed.

Figure 12 shows a modification of the inner container and especially of the closure parts thereof.

Figure 13 shows the same partly closed.

Figure 14 shows another modification of inner container construction.

Figure 15 shows another modification in which the end portions of the connecting strip are exposed for attachment to the outer wrapper.

Figure 16 shows the outer wrapper applied and secured to the inner container of Figure 15.

Figure 17 shows the closure end or neck of Figure 16 partly folded or closed.

Figure 1 shows a composite inner wrapper sheet S suitable for packages of this class, consisting of an outer sheet F, of tin-foil and an inner sheet P of paper, these sheets being usually secured together by spaced stripes of adhesive *a*. Usually these

composite sheets or blanks are of rectangular form, requiring tuck-fold formations at the mouth end of the inner container or wrapper, which make the package unduly bulky at the mouth and interfere with the proper flat closure formation of the outer wrapper, as briefly referred to above. To avoid these difficulties the blank S in some cases is "cornered" by cutting away rectangular portions and leaving flaps 1, which may be conveniently identified as side mouth flaps or otherwise, as shown in Figure 2, the blanks may be merely slit longitudinally for a short distance near each longitudinal edge 2, these slits 3 defining side mouth flaps 1 as in the previous instance, and also what may be conveniently identified as narrow end mouth flaps 4.

I will first describe the further formation of a complete package including a cornered blank, such as shown in Figure 1, without the narrow end mouth flaps. Since it is easier to explain the structure of these containers or packages by describing the method of producing them I will generally herein describe the production of the packages with certain elementary devices, or parts of suitable mechanism, for such purposes, but it is to be understood that the process of production does not form a part of the present invention, and novel features of the production methods will be described and claimed in separate applications.

For the convenient production of a representative package employing the blank of Figure 1, a plunger K, Figure 3 is employed, having broad sides 6 and narrow sides 7 and an end 8, and the container is formed upon this plunger. A strip R of paper of suitable thickness, usually somewhat thicker than the relatively thin lining paper P of the composite blank S, is provided, of suitable length and of a width equal to the width of the plunger end 8 and sides 7. The central part 9 of this strip, which may be identified as a connecting or reenforcing strip, is applied to the end of the plunger as sufficiently indicated in Figure 3, and the end portions 10 of the strip are then folded along plunger sides 7. Adhesive is applied to the outer surface of the strip at any suitable state of the operations, before or after it is applied to the plunger, this adhesive *g* being indicated by stippling in Figure 4 and following figures.

A blank S (Figure 1) is now positioned in relation to the plunger, as shown in Figure 4, with the paper surface of the composite blank confronting the plunger, and the end of the plunger with its superposed reenforcing strip is brought against a central area 11 of the blank S, indicated by dotted lines. This area 11 constitutes the bottom of the inner container. Adhesive connection is thus provided between the cen-

tral portion 9 of the reenforcing strip and the bottom area of the composite wrapper. Portions 13 and 14 of the wrapper are now folded upon the broad sides 6 of the plunger, leaving side margins 15 and bottom end margins 16 projecting beyond the narrow plunger sides 7, and with the side mouth flaps 1 previously mentioned, lying upon broad sides 6 of the plunger. As shown in Figure 5, it is now evident that in this particular embodiment of the invention the reenforcing strip R is of such length that its ends 17 terminate flush with the ends 18 of blank margins 15.

15 The projecting bottom margins 16 are now tucked in or folded against adhesively coated surfaces of strip R, and the projecting side margins 15 are then successively folded down and adhesively secured to the side portions 10 of strip R, as shown in Figure 7. In these operations inner paper surfaces of the composite wrapper are brought into adhesive connection with the paper reenforcing and connecting strip and therefore a very firm and permanent connection is provided for these parts insuring the retention of the inner container in the proper shape. Especially infolded or tuck-folded flaps 16 which in the ordinary construction 25 of these pouches are entirely unsecured and subject to displacement as previously mentioned, are firmly secured and prevented from dislocation in the further operations upon the container or in filling the container after its completion.

30 The provision of the reenforcing strip also provides for the proper positioning and retention of the side margins 15, even if these margins are not properly overlapped, as sufficiently indicated in Figure 14, where the inner composite wrapper may have been intentionally or inadvertently cut so that these margins will not meet or overlap, or else by careless production methods or for 35 other reasons the overlap has not been properly effected, but the margin portions 15 are nevertheless securely connected and the inner container is held in form by the reenforcing strip R.

40 Such an inner container is usually completed by the application of an outer envelope or wrapper W, Figure 7. This wrapper is usually of paper of rectangular form and with suitable indicia printed on its outer surface. The outer wrapper may be applied and folded over the inner wrapper or container, while the latter is on the plunger, substantially in the same manner as the inner wrapper is formed about the plunger, the successive steps of folding the outer wrapper being sufficiently indicated in Figures 7 to 11 inclusive. Adhesive may be applied at any suitable stages of the operations to secure the longitudinal overlapping margins 20 of the wrapper, tuck-folds

45 21 being formed at the bottoms of the narrow side walls, substantially as in the case of the inner container.

50 The outer wrapper is usually cut so that when the formation of the container is completed, except the top closure, as in Figure 8, the mouth edges 22 of the outer wrapper extend outward, at least as far as the edges 23 of side mouth portions 1 of the inner wrapper; or the edges 22 may extend moderately beyond edges 23. The package may now be filled with any suitable pulverized or comminuted content material, such as smoking tobacco in the form of cut plug, granulated scrap or fine cut 55 for chewing, the tobacco contents being sufficiently indicated at T, Figure 8. The package is now ready for closing. In packages of this class, as heretofore made, the mouth or neck portions of the inner wrapper or 60 container extending above the tobacco contents include not only broad side marginal portions 1, but narrow end portions continuous therewith, and extending from the narrow side folds 15, since the blank usually 65 employed is rectangular, without the cut-away portions as shown in Figure 1. The folding down of the neck portions of the inner container therefore entails ordinarily the formation of tuck-folds, and it is 70 difficult to form these folds either by machine or hand operations, and moreover, the folds make the end of the inner package unduly bulky and it is difficult to completely and smoothly fold down the neck or 75 mouth of the outer wrapper.

80 With my invention, however, as so far explained, there are no end portions in the neck structure of the inner wrapper, and it is only necessary to fold down the side 85 mouth flaps or margins 1 successively in overlapped relation, as shown in Figure 9. A perfectly flat inner package end is thus produced, and the outer wrapper may then be closed flat and smooth upon the inner end 90 formation, by the ordinary tuck-fold arrangement, as sufficiently shown in Figures 10 and 11. Similarly, when the package has once been opened by the consumer, it is a 95 simple and easy operation for him to fold 100 down the straight mouth flap 1, with no difficulty such as is incident to the end-fold formations of the ordinary package.

105 Figures 12 and 13 sufficiently illustrate variations in package construction suitable 110 for the use of an inner composite blank of the character shown in Figure 2, that is, one in which narrow end mouth flaps 4 are provided as well as side mouth flaps or margins 1. The reenforcing strip in this case is 115 of a length equal to the length of the inner wrapper, and ends 17 of the reenforcing strip therefore are coterminous with the ends of flaps 4. In closing the mouth of the inner container after the package is filled, the 120

125 130

mouth end flap formations comprising the flaps 4 and the ends of the reenforcing strip, are first folded down upon the tobacco contents, Figure 13 and then the side mouth flaps 1 which were separated from the end flaps 4 by slits 3 in the formation of the blank, Figure 2, are folded down substantially in the same way as previously described, this arrangement permitting a smooth and flat end fold, because of the avoidance of any necessity for tuck-fold formations.

Figures 15 to 17 show another variation in package structure in accordance with which the inner composite blank is formed substantially as in the first instance, that is, in accordance with Figure 1, but the reenforcing strips are of substantially the same length as described in connection with Figures 4 to 7; that is to say, they are as long as the ends of the side mouth flaps 1, although the longitudinal marginal portions 15 of the composite wrapper terminate at the points 18, considerably below the ends 25 of the reenforcing strip. When the inner container is formed, as described in Figures 1 to 7, therefore, adhesively coated end portions 30 of the reenforcing strip are exposed beyond the ends of wrapper margins 15. The outer wrapper is then applied as in the previous case and end portions of the wrapper narrow side folds or margins 20 are pressed against and adhesively connected to the reenforcing strip ends 30, producing composite outer wrapper and reenforcing strip portions 31, Figure 16. When the package is filled it is closed by first turning down side mouth flaps 1, and then the portions 31 are tuck-folded or turned in as indicated at 32, Figure 17, and then the wrapper neck portions 33 are turned down and secured, as in Figure 11, which shows the upper end formation of the completed package.

In some cases, and especially when the packages are of considerable size, cards 40 are inserted at the bottom of the container and also within the top or neck of the inner container, serving to stiffen and maintain the rectangular end formation of the package. When the package is opened the upper card 40 is usually taken out and thrown away, and the package closure is manipulated as previously described until the contents is exhausted.

What I claim is:

1. A package or container for tobacco or other commodities as set forth, comprising an inner wrapper consisting of an inner layer of paper and an outer layer of foil, 60 in substantially rectangular pouch form, with closed bottom and folded longitudinal narrow side margins and bottom end margins intucked beneath the narrow side margins, an internal securing strip adhesively 65 secured to the bottom, bottom end tucks and longitudinal narrow side margins of the paper layer of the composite wrapper and securely retaining the inner wrapper in substantially rectangular form, and also securing the infolded bottom end tucks against displacement, and an outer wrapper enclosing the inner wrapper and having a foldable closure neck.

2. A container for tobacco or similar 75 commodities, comprising an inner container or wrapper of composite foil and paper, the paper layer being arranged as the lining of the composite wrapper, the cross-sectional form of the container being substantially 80 oblong, the inner wrapper being formed with a solid bottom and with tuck-folds on the narrow sides adjacent to the bottom and with infolded portions along the narrow sides overlying the tuck-folds, a reenforcing and securing strip adhesively secured to the bottom of the inner wrapper and to the infolded narrow side portions thereof, the wrapper being formed with broad side closure flaps, and narrow end closure flaps 90 adhesively secured to the reenforcing and securing strip, said broad and narrow closure flaps being severed at their intersections and all said flaps extending substantially 95 above the normal contents level of the inner container, the described closure flap arrangement permitting the flaps to be turned smoothly down upon the container contents without tuck-folds to provide a flat and smooth package top, and an outer wrapper 100 enclosing the inner wrapper or container and having a neck extending substantially above the package contents and arranged to be tuck-folded to cover the closure members of the inner container.

Signed at New York, New York in the county of New York and State of New York this 16th day of July A. D. 1923.

JONATHAN PETERSON.
